DESIGN FOR A MOLDING.

SPECIFICATION forming part of Design No. 16,860, dated August 17, 1886.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 16,860, dated August 17, 1886.

Application filed July 1, 1886. Serial No. 206,867. Term of patent 7 years.

To all whom it may concern:

Be it known that I, FREDERICK MANKEY, of Williamsport, Lycoming county, Pennsylvania, have invented and produced a new and 5 original Design for Ornamental Trims or Moldings, of which the following is a specification, reference being had to the accompanying photograph, forming part hereof.

My design relates to an ornamental trim or molding in the form of a band or bar; and it consists in the configuration thereof substantially as represented. On each edge of the band appears a series of scallops, A, the scallops on one edge being disposed opposite to 15 the meeting-points of the scallops on the op-

posite edge. On the face of the band, and extending diagonally across the same and between the meeting-points of scallops on opposite sides, are lenticular depressions C.

I claim—

The design for an ornamental trim or molding, substantially as herein shown and described, which consists in the scallops A on opposite edges of said trim, and on the face thereof the lenticular depressions C.
